(57) **CLAIM**

The ornamental design for a solar powered light, as shown and described.

DESCRIPTION

FIG. 1 is a front view of a solar powered light, incorporating my new design, the rear view being a mirror image thereof; FIG. 2 is a side view thereof, the opposite side view being a mirror image thereof;

FIG. 3 is a top plan view thereof on an enlarged scale;

FIG. 4 is a bottom view thereof on an enlarged scale;

FIG. 5 is a perspective view thereof;

FIG. 6 is a front view thereof in a first alternative configuration;

FIG. 7 is a front view thereof in a second alternative configuration;

FIG. 8 is a front view thereof in a third alternative configuration;

FIG. 9 is a front view thereof in a fourth alternative configuration;

FIG. 10 is a perspective view thereof in a fifth alternative configuration; and,

FIG. 11 is a perspective view thereof in a sixth alternative configuration.
